GRINDING MACHINE AND METHOD

John Edgar, Rockford, Ill., assignor to Barber-Colman Company, Rockford, Ill., a corporation of Illinois

Application July 9, 1930, Serial No. 466,764
Renewed December 12, 1935

33 Claims. (Cl. 51—50)

The present invention relates to improvements in grinding machines, and has particular reference to a new and improved machine for and method of grinding rotary thread milling cutters.

5 One of the objects of the present invention is to provide a novel grinding machine which will correctly form grind the teeth of rotary thread milling cutters having either straight, helical or inclined gashes, and being either cylindrical or 10 tapered axially in form, the operation after the initial setting being fully automatic.

Another object resides in the provision of a new and improved grinding machine of the foregoing character which may be operated either automatically, semi-automatically or manually.

15 A further object is to provide a novel grinding machine for rotary thread milling cutters which is operable to take a series of light cuts successively along the blank until ground to the desired depth, thereby effecting an even distribution of heat and hence avoiding distortion and unevenness.

Another object resides in the provision of novel dressing means for the grinding element which 20 after the initial setting is automatically adjusted to compensate for the progressive depth feed of the grinding element, and which more specifically is automatically effective upon manual repeated actuation after successive feeding movements of 25 the grinding element toward the work to gradually change the cutting contour of the grinding element from a blunt form to a sharp V-shaped form, and to limit the abrasive action as to depth and form.

30 Further objects and advantages will become apparent as the description proceeds.

In the accompanying drawings, Figure 1 is a fragmentary plan view of a machine embodying the features of my invention.

40 Fig. 2 is a fragmentary detail sectional view taken along line 2—2 of Fig. 4.

Fig. 3 is an enlarged plan view, partially in section, of the grinding wheel spindle head.

While the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and

10

15

20

25

50

55

alternative constructions falling within the spirit and scope of the invention as expressed in the appended claims.

Referring more particularly to the drawings, 5 the machine constituting the exemplary embodiment of the invention is adapted primarily for grinding thread milling cutters of the ring type. Cutters of this type comprise a plurality of radially relieved, substantially V-shaped teeth which are 10 arranged in parallel peripheral rows alternating with annular grooves and which are separated by longitudinal flutes or gashes. The gashes may be either parallel or inclined in either direction to the cutter axis. In the present instance, I 15 have shown a thread milling cutter A with right-hand inclined gashes.

The grinding element preferably comprises an abrasive disk wheel B, the periphery of which is adapted to grind the annular cutter grooves 20 and thereby form the cutter teeth, and the cutting contour of which is V-shaped in form when taking the final depth cut.

In the grinding operation, the cutter blank A is rotated slowly, and the grinding wheel B is 25 driven at a relatively high speed. At the start of the operation, the blank and the wheel are relatively adjusted laterally of the blank to effect a light initial cut and longitudinally of the blank to grind the first groove on one end. A relative 30 reciprocation between the blank and the wheel transversely of the blank is imparted once for each tooth and in timed relation to the rotation of the blank to provide the proper relief. When the blank has been rotated sufficiently to present 35 all of the teeth in the initial row to the wheel, i. e. through one complete revolution where the teeth are ground consecutively, the cutter and the blank are separated, and during the next complete revolution of the blank are indexed 40 into position to grind the next annular groove. When grinding a blank with inclined gashes, the idle rotation of the blank is adjusted during each indexing step to compensate for the lead of the gashes. In the present instance involving right-hand gashes, a slight additional degree of rotation 45 is imparted to the blank.

The foregoing operation is repeated until all of the rows of teeth have been ground with an initial cut, i. e. until the entire length of the 50 blank has been traversed by the grinding wheel in a step-by-step grinding stroke. Thereupon, the blank and the grinding wheel are separated, and the latter is returned in a relative free continuous indexing stroke at a high speed to its 55 initial position, and is given a relative incremental feed toward the blank preparatory to taking the second cut. Successive cuts along the blank are taken until the teeth are ground to the desired depth.

60 One feature of the invention resides in changing the form of the cut progressively with successive grinding strokes along the blank from a blunt contour to the final V-shaped contour. This is accomplished by automatically effecting 65 an incremental feed of a suitable dressing tool toward the grinding wheel once for each incremental feed of the latter toward the blank so that in repeated truing of the grinding wheel its cutting contour will be changed in accordance 70 with the desired change in the tooth form as the grinding progresses to depth.

A relative compensatory adjustment of the 75 grinding wheel laterally of the blank in timed relation to the indexing movement and the quick return is available for grinding tapered cutters.

The present machine for carrying out the foregoing operations may be set up at will for fully automatic, semi-automatic or manual operation.

Work support and drive

The machine comprises a suitable elongated horizontal bed or frame 31 formed on the top with longitudinal guides 32 on which a work carriage 33 is mounted for translation. The right end of the carriage 33 is formed on the top with 10 longitudinal guides 34 on which a suitable tailstock 35 is mounted for adjustment. On the left end of the carriage 33 and preferably integral therewith is a headstock 36 formed with a tubular bearing 37. A cutter spindle 38 is rotatably journaled in the bearing 37 for endwise movement with the carriage 33, and has an arbor section 39 on which the cutter blank A is removably mounted. The free end of the arbor section 39 is supported by the tailstock 35.

The power inlet comprises a cone pulley 40 which is secured to a short drive shaft 41 journaled at the upper left front corner of the frame 31, and which is adapted to be connected by a belt 42 to an external countershaft (not shown) 25 adapted to be connected through a reversible clutch (not shown) to a suitable source of power. A drive pinion 43 on the shaft 41 meshes with a large drive gear 44 rotatably mounted on a hollow shaft 45 into which the left end of the spindle 30 38 is splined for relative axial movement.

The gear 44 has a hub 46 projecting from both sides, and is formed in its right face with an annular concentric cavity 47. An adjusting disk 48 is mounted for rotary adjustment on the gear 35 hub 46 within the cavity 47, and is formed with an annular T-slot 49 opening to the face of the gear 44. A plurality of bolts 50 carried by the gear 44 and with their heads in the slot 49 serve as means for securing the disk 48 in position of adjustment to the gear. This adjustment permits setting the gashes of the work in proper relation to the grinding wheel B.

A pair of diametrically opposed studs 51 are mounted on the disk 48 and project from the 45 outer face thereof. Rotatably mounted on each of the studs 51 is a pair of gears 52 and 53 of which the outer gear 52 is the smaller. The outer gears 52 mesh with a terminal gear 54 formed on a sleeve 55 journaled on the shaft 45, 50 and normally held in fixed position, and the inner gears 53 mesh with a terminal gear 56 keyed to the shaft 45. It will thus be evident that the gear 44 is the driving element of a planetary gear 55 transmission for slowly rotating the work spindle 38.

Indexing mechanism

The relative step-by-step indexing movement and the free-return movement of the grinding wheel B along the blank A are obtained by driving the slide or carriage 33 in timed relation to the rotation of the blank. The drive means for this purpose (see Figs. 1 and 16) derives its power from the gear 44 through a gear 57 keyed to the hub 46. The gear 57 is connected through an idler gear 58 to a gear 59 keyed to a shaft 60 extending along and journaled on the rear of the frame 31.

Secured to the hub of the gear 59 is a gear 61 in mesh with a gear 62 rotatable on a sleeve 63 in turn rotatable on a fixed stub shaft 64. A suitable clutch 65 comprising a single clutch tooth on the hub of the gear 62 and a similar opposed clutch tooth on one end of a clutch sleeve 66 70 75

axially splined to the sleeve 63 is provided for connecting and disconnecting the gear 62 and the sleeve 63. The clutch 65 is always closed during the full automatic operation of the machine.

- 5 An annular collar 67 is keyed to the sleeve 63, and extends partially into a central recess 68 formed in the hub of a mutilated gear 69 rotatably mounted on the shaft 64. The collar 67 is formed in its periphery with a notch 70 (see Fig. 20) normally engaged by a spring-pressed pawl 71 pivotally mounted in the hub of the gear 69, and is effective through the pawl to drive the gear in a counter-clockwise direction as viewed in Fig. 20, but not in the reverse direction.
- 10 15 The toothed sector of the gear 69 is movable once during each rotation into mesh with a gear 72 rotatable on a stub shaft 73 in axial alinement with the shaft 60, and is adapted to rotate the gear through one complete revolution during each engagement. The stub shaft 73 is suitably journaled on the frame 31 and in the adjacent end of the shaft 60.

20 Secured to and concentric with the gear 69 is a circular disk 74 (see Fig. 17) which is notched at 75 in the region of the gear sector to receive the periphery of a disk 76 secured to and concentric with the gear 72 so as to permit rotation of the latter when in mesh with the sector, and which is adapted to engage in an arcuate notch 77 in the periphery of the disk 76 to lock the latter against rotation when the gear sector is out of mesh with the gear 72. The construction thus constitutes a modified form of Geneva motion device.

25 30 35 As an additional means for locking the gear 72 in fixed position when out of mesh with the mutilated gear 69, the disk 76 is formed in its periphery with a notch 78 slightly tapered inwardly. A plunger 79 slidably disposed in a vertical guide 80 (see Fig. 20) on the frame 31 is formed on its upper end with a tooth 81 adapted to enter the notch 78 and thereby accurately locate and lock the gear 72 in position, and on its lower end with a gear rack 82. A gear sector 83 secured to a stub shaft 84 meshes with the rack 82, and is urged upwardly by a coil spring 85. Also secured to the shaft 84 is a cam arm 86, the free end of which projects into the path of a cam block 87 secured to the right face of the gear 69. The cam block 87 is located to depress the follower arm 86 and thereby withdraw the tooth 81 from the disk 76 just before the gear 69 moves into mesh with the gear 72, and to release the arm and thereby restore the tooth into engagement with the disk so that the tooth will snap into the notch 77 when the gear 72 has made one complete revolution.

40 45 50 55 Axially splined on the shaft 13 between the gears 59 and 72 is a clutch sleeve 88. One end of the sleeve 88 is formed with a single tooth adapted to be moved into coacting engagement with a similar opposed tooth on the hub of the gear 72, the teeth constituting a clutch 89 for connecting the latter to the shaft 73. The other end of the sleeve 88 and the hub of the gear 59 are formed with the opposed elements of a clutch 90 movable into engagement to connect the gear 59 to the shaft 73.

60 65 70 75 The outer end of the shaft 73 is connected through speed-change gears 91, 92 and 93 (see Figs. 9 and 10) to a shaft 94 journaled in the left end of the frame 31. A screw shaft 95 is journaled at its ends in the inner end of the shaft 94 and the right end of the frame 31, and is formed with a feed screw 96 in threaded engagement with a

fixed nut 97 in a depending lug 98 on the underside of the carriage 33. Back-lash between the feed screw 96 and the nut 97 is taken up by a weight 99 (see Fig. 8) connected to the right end of the carriage 33 through a cord 100 leading over a pulley 101 in a bracket 102 on the right end of the frame 31.

75 80 85 90 95 100 A clutch 103 comprising opposed clutch elements on the inner end of the shaft 94 and the adjacent end of a clutch sleeve 104 splined for axial movement on the shaft 95 is provided for connecting the two shafts. A shifting yoke 105 engages the sleeve 104 and is secured to a rock shaft 106 extending to the front of the frame 31 and there provided with a suitable hand lever 107. The clutch 103 is closed during full automatic or semi-automatic operation of the machine, and is opened for manual operation.

105 110 115 120 125 It will be evident that when the clutch 89 is closed, the indexing drive will be connected from the gear 59 through the Geneva motion device to the shaft 73 and thence to the feed screw 96 to index the cutter A in a step-by-step grinding stroke to the right to effect a relative movement of the grinding wheel B to the left. The gearing is such that each indexing movement is just sufficient to move the succeeding peripheral groove between the teeth into operative registry with the grinding wheel.

130 135 140 145 150 Upon opening the clutch 89 and closing the opposed clutch 90, the gear 59 will be connected directly to the shaft 73 and thence to the feed screw 96, thus constituting a continuous rapid drive. Under the last condition, the rotation of the gear 59 must be reversed to move the cutter A in a quick-return stroke to the left into its initial position for the next depth cut. However, upon such reversal, the collar 67 will be ineffective to rotate the mutilated gear 69, and hence the Geneva motion device will remain idle.

155 160 165 170 175 Means is provided for reversing the clutch sleeve 88 to alternately close the clutches 89 and 90 respectively at the end of the grinding stroke to the right and the quick-return stroke to the left, and for simultaneously reversing the rotation of the gear 59 from which both drives are taken. This means (see Figs. 22, 23, and 24) preferably comprises a fluid operated engine 108 having a cylinder 109 mounted on the rear of the frame 31. A piston 110 is slidably disposed in the cylinder 109, and is connected to a piston rod 111 projecting at both ends through the cylinder heads.

180 185 190 195 200 The left end of the piston rod 111 (as viewed from the front of the machine) extends slidably through an eye 112 (see Figs. 8 and 20) on the lower end of a lever 113 pivoted at its upper end. Two coil springs 114 are disposed on the rod 111 with their adjacent ends in abutting engagement with opposite sides of the eye 112 and with their remote end in abutting engagement with spaced stop collars 115. The lever 113 is formed intermediate its ends with a bifurcated portion which carries a shifting ring 116 in engagement with the clutch sleeve 88.

205 210 215 220 225 The right end of the rod 111 is formed with a yoke 117 which engages a roller 118 mounted on the free end of a lever 119 secured to a vertical shaft 120. The upper end of the shaft 120 is connected to suitable actuating means (not shown) for the reversing clutch (not shown) in the countershaft (not shown) adapted for connection through the belt 42 with the cone pulley 40.

230 235 240 245 250 The cylinder 109 is formed with suitable pas-

5 sages 121 and 122 opening respectively to opposite ends of the cylinder chamber, and through peripherally spaced ports 123 and 124 to a vertical valve chamber 125. The lower end of the chamber 125 is adapted for connection through a line 126 to a suitable source (not shown) of pressure fluid, such for example as compressed air. A valve plug 127 is rotatably mounted in the chamber 125, and is formed with an axial bore 128 in 10 its lower end in communication with the inlet line 126, and opening to the periphery through a radial port 129 movable into registration with either of the ports 123 and 124. The exterior of the plug 127 is formed with a peripheral space 15 130 terminating adjacent opposite sides of the port 129, and communicating through a radial bore 131 with an axial bore 132 exhausting to the atmosphere.

Secured to the upper end of the valve plug 127 20 is a bell crank lever 133 (see Figs. 16 and 22). A coil tension spring 134, anchored to the frame, is connected to one arm of the lever 133 and tends to swing this arm against a fixed stop pin 135. The other arm of the lever 133 constitutes a pawl 25 136 adapted to be swung against the action of the spring 134 into interlocking engagement with the notched end of a latch 137. A lever arm 138 is pivotal with the latch 137, and is connected at its free end to a coiled tension spring 139 anchored to the frame 31 and serving to hold the latch against the pawl 136 at all times.

The pawl 136 when seated in the latch 137 defines one position of the plug in which the port 129 registers with the port 123 to direct pressure fluid to the right end of the cylinder, and in which the space 130 communicates with the port 124 to vent the pressure fluid in the left end of the cylinder to the atmosphere. The resultant movement of the piston 118 to the left serves to close 40 the clutch 90 and to change the rotation of the work spindle 38 and the gear 59 so that the blank A will be rotated in a counter-clockwise direction as viewed in Fig. 12, and the timed step-by-step indexing movement to the right will be instituted.

45 A trip dog 140 mounted on the carriage 33 for movement therewith has an inclined surface adapted to ride against a pin 141 extending upwardly from the free end of the lever arm 138, and to gradually swing the latter rearwardly until at the end of the indexing movement, the latch 137 releases the pawl 136. Thereupon, the lever 133 is moved under the influence of the spring 134 into engagement with the stop pin 135. The latter defines the other position of the 50 valve plug 127 in which a port 129 registers with the port 124 to direct pressure fluid to the left end of the cylinder, and in which the space 130 communicates with the port 123 to vent the pressure fluid in the right end of the cylinder to the 55 atmosphere. The resultant movement of the piston 118 to the right serves to close the clutch 90 and to change the rotation of the work spindle 38 and the gear 59 so that the blank A will be rotated in a clockwise direction as fluid in Fig. 12 60 and a quick-return movement to the left will be instituted.

65 A reversing dog 142 mounted on the carriage 33 for movement therewith is positioned to engage the free end of the lever 133 at the end of the quick-return movement, and to move the same against the action of the spring 135 into position for engagement by the tooth of the latch 137, thereupon reinstating the step-by-step indexing movement preparatory to taking a new 70 depth cut on the work.

When the blank A is formed with inclined gashes, the work spindle 38 is angularly adjusted proportionately with each step in the indexing movement so as to compensate for the inclination of the gashes. This adjustment may be positive or negative depending on whether the blank A has right-hand or left-hand gashes. In the present instance, the blank A is shown with right-hand gashes, and hence is turned through one complete revolution plus the additional compensatory rotation during each increment in the indexing movement. The means for this purpose (see Figs. 4, 7, and 16) comprises a gear 143 formed on the sleeve 55 which supports the terminal gear 54 of the planetary spindle drive. 15 The gear 143 is connected through an idler gear 144 to a gear rack 145 formed on the lower end of a bar 146 vertically reciprocable in a guide-way 147.

20 The upper end of the bar 146 carries a pivotal block 148 which is slidably disposed in a longitudinal guide-way 149 formed in a horizontal bar 150. The bar 150 is pivoted adjacent one end as indicated at 151, to a horizontal bar 152 of which one end is rigidly secured to an upstanding bracket 153, mounted on the work carriage 33 for movement therewith, and of which the other end is slidably disposed in a horizontal guide 154 formed on the upper end of an upstanding bracket 155 on the machine frame. The free end of the pivotal bar 150 constitutes a pointer movable along an arcuate scale 156 formed transversely on the horizontal bar 152, and carries a clamp bolt 157 adjustable in an arcuate slot 158 extending along the scale. When the pivotal bar 150 is secured in a horizontal position at the zero point on the scale 156, no movement will be imparted to the rack 145 upon translation of the carriage 33 in either direction, and hence the terminal gear 54 will be stationary. However, if the pivotal bar 150 is adjusted above or below the zero point of the scale 156 at an angle corresponding to that of the cutter gashes, translation of the carriage 33 30 will impart a reciprocatory movement to the rack 145, thereby effecting a compensatory drive 35 through the terminal gear 54 as aforesaid.

40 The periodic indexing for the carriage 33 is subject at will to manual control so as to facilitate properly locating the grinding wheel B relative to the tooth grooves of the blank in setting up the machine, and to permit rough grinding. The means for this purpose (see Figs. 16, 18 and 25 to 27) comprises a shoe 159 engaging a peripheral groove 160 in the clutch sleeve 66, and secured to the lower end of a lever 161 pivotally mounted 55 intermediate its ends as at 162 on a bracket 163. The upper end of the lever 161 is connected to a shifter rod 164 (see Figs. 1 and 8) extending along the rear of the machine and slidably supported in a bracket arm 165 on the machine frame 31. A 60 suitable handle 166 is secured to the free end of the rod 164 which is capable of actuation to close the clutch 65 and institute the indexing operation.

65 The clutch 65 is opened automatically upon indexing the blank A the distance between two tooth grooves. To this end, an L-shaped bracket 167 is secured to the right face of the gear 62. A star wheel 168 is rotatably mounted on a stud 169 secured to the outwardly extending arm of 70 the bracket 167, and consists of a triangular prism with a similar triangular prism superimposed on the inner end, thus providing three equi-angular points at the outer end and six equi-angular points at the inner end. A spring- 75

pressed detent 170 mounted in the base of the bracket 167 is formed in its outer end with a V-shaped notch adapted to engage any one of the six points of the star wheel 168.

5 Pivots mounted on a bracket 171 in the machine frame 31 is a pawl 172, the heel of which is pressed by a spring 173 against a stop pin 174. The pawl 172 projects into the path of the six points of the star wheel 168, and constitutes a 10 fixed abutment for indexing the star wheel through one-sixth of a revolution once for each revolution of the gear 62. A pawl 175 pivotally mounted on the lower end of the lever 161 and with its heel pressed by a spring 176 into engagement with a stop pin 177 projects into the path of the triangular portion of the star wheel 168, and is adapted for engagement by one of the three points through two indexing movements of the star wheel once for every two revolutions of the gear 62 to automatically open the 15 clutch 65. The pawl 175 is mounted on the lever 161 only when the operation is to be semi-automatic, and is removed for full automatic operation. It will be evident that in semi-automatic 20 operation, the clutch 65 is closed manually to institute each indexing movement, and that it will be opened automatically when the blank A has been indexed exactly one groove.

30 Grinding wheel support

The grinding wheel B is mounted on one end of a drive spindle 178 (see Fig. 3) which is rotatably mounted in a spindle head 179 slidably adjustable on ways 180 formed on the end of a 35 suitable bracket support 181. An adjusting screw 182 rotatably anchored on the bracket 181 is in threaded engagement with the spindle head 179. Secured to the spindle 178 within the head 179 is a pinion 183 which is connected through an 40 idler gear 184 to a gear 185, both gears 184 and 185 being mounted on the side of the bracket 181. A sheave 186 is rigid with the gear 185, and is adapted to be connected through a belt 187 to a suitable source of power (not shown).

45 The bracket 181 is mounted between two spaced upstanding supports 188 and 189 (see Figs. 28 and 30) for pivotal adjustment about a horizontal shaft 190 extending perpendicularly to the blank axis, and is adapted to be secured 50 to the support 188 by means of a locating pin 191 and a bolt 192 in either of two horizontal positions at opposite sides of the shaft 190, thus locating the grinding wheel B in position to engage the blank A in a horizontal axial plane.

55 The supports 188 and 189 are formed on a horizontal feed slide 193 (see Figs. 11 and 12) mounted for adjustment transversely of the blank A along ways 194 on a horizontal supporting slide 195. A feed screw 196 in threaded engagement with a nut 197 on the underside of the slide 193 is journaled in a bearing bracket 198 on the front end of the slide 195. The outer end of the feed screw 196 (see Figs. 5 and 12) is provided with an enlarged head 199 rotatable 60 in a seat 200 formed in the front face of the bracket 198. A cylindrical block 201 is notched at its inner end to interfit with an annular peripheral end flange 202 formed on the outer end of the head 199, and is rigidly secured to the latter by means of bolts 203. The flange 202 is somewhat larger in diameter than the block 201, and hence defines an outwardly facing peripheral shoulder 204 about the latter. A cam abutment 205 is seated in a recess in the front end of the block 201 and projects forwardly therefrom.

Extending slidably through aligned axial bores 206, 207, and 208 in the screw 196, the block 201 and the abutment 205 is an elongated draw bolt 209, the rear end of which is in fixed threaded engagement with a lug 210 on the supporting 5 slide 195 and the front end of which is formed with a bearing ring or eye 211. A bifurcated rotary cam 212 provided with a hand lever 213 is pivotally mounted on opposite ends of a pin 214 extending through the eye 211 in bearing 10 engagement with the cam abutment 205, and serves as means for anchoring the feed screw 196 rigidly to the slide 195. A coiled compression spring 215 is disposed on the draw bolt 209 within an enlargement 216 of the inner end of 15 the bore 206 in end abutment with the inner end of the enlargement and the front of the lug 210, and serves upon releasing the cam 212 to shift the feed screw 196 forwardly in the bearing 198, and thereby retract the grinding wheel B from 20 the blank A into inoperative position.

A relative automatic feed increment toward the blank A is imparted to the grinding wheel B once for each longitudinal cut. The means for this purpose (see Figs. 1, 2, 4, 5, and 6) comprises 25 a gear 217 formed on the front end of the block 201, and disposed in a circular recess 218 formed centrally in the front face of a large gear 219 freely rotatable on the block 201. Journalized in and extending through the web of the gear 219 30 at diametrically opposed points are two stub shafts 220 and 221. A pair of gears 222 and 223 are secured respectively to the front ends of the shafts 220 and 221 in mesh with the gear 217, and are suitably disposed in circular recesses 224 35 and 225 formed in the front face of the gear 219. Likewise, a pair of gears 226 and 227 are secured respectively to the rear ends of the shafts 220 and 221 within suitable circular recesses 228 and 229 formed in the rear face of the gear 40 219.

The gears 226 and 227 mesh through idler gears 230 and 231 with a gear 232 which is disposed in a central circular recess 233 formed in the rear face of the gear 219, and which is secured to the 45 front face of a gear 234 rotatably mounted on the block 201 and abutting against the flange shoulder 204. Thus, the parts are held in assembled relation between the shoulder 204 and the gear 217. Normally, the gear 234 is held 50 against rotation in position of adjustment by means of a spring-pressed lock pin 235 mounted in a side bracket 236 on the slide 195 for engagement between the gear teeth. It will be evident that the gear 219 constitutes the driving element 55 of a planetary gear transmission for the feed screw 196 of which the gear 232 is the fixed terminal gear, and the gear 217 is the outlet terminal gear. The gear 219 meshes with a worm 237 on a vertical shaft 238 journaled in the bracket 236, and is provided with a suitable hand wheel 239 on its upper end.

The lower end of the shaft 238 is provided with a ratchet 240 and supports a pivotal pawl arm 241 (see Fig. 2) directly over the latter. A pawl 65 242 is pivotally mounted on the underside of the arm 241 for engagement with the ratchet 240, and is movable at will into inoperative position against a stop 243. A bent leaf spring 244 anchored on a pin 245 on the arm 241 has one 70 end in engagement with the stop 243 and the other end is flexed engagement with the heel of the pawl 242, and serves to hold the pawl yieldingly in either extreme position.

The free end of the arm 241 is connected 75

through a rod 246 to one arm of a bell-crank lever 247 pivotally mounted on the slide 195. The other arm of the lever 247 carries an adjustable stop screw 248 adapted to engage the slide 195 to define the starting point of the working stroke of the pawl 242, and is disposed in the path of a dog 249 on the work carriage 33 for engagement thereby at the end of the free-return stroke. A coiled tension spring 250 secured at its ends to the lever 241 and an anchor pin 251 on the slide 195 tends to hold the screw 248 against the slide.

Suitable means is available for imparting a transverse movement to the grinding wheel B in timed relation to the indexing movement of the blank A when grinding taper work. This means (see Figs. 1, 4, and 9) preferably comprises a spiral gear 252 on the feed screw shaft 95 and meshing with a spiral gear 253 on a transverse shaft 254 extending to the front of the frame 31. The front end of the shaft 254 is squared for the reception of a suitable hand lever (not shown), and supports a pivotal change gear bracket 255. A gear 256 on the shaft 254 meshes with a change gear 257 adjustable on the bracket 255 and movable into engagement with the gear 234. When the gears 234 and 257 are brought into mesh, the lock pin 235 is withheld from the gear 234, and the feed screw 196 for the slide 193 will be actuated in timed relation to the feed screw 96 for the carriage 33.

Dressing mechanism

Means is provided for dressing the grinding wheel B from time to time to maintain the desired form and to remove glaze from the grinding surface. This means (see Figs. 28, 29, and 30) is mounted on and includes the shaft 190 rotatably adjustable in the supports 188 and 189. A positioning disk 258 is keyed to the front end of the shaft 190 and is adjustably disposed in a recess 259 formed in the rear side of the support 188. Clamp bolts 260 with their heads disposed in an annular T-slot 261 in the front face of the disk 258 are provided for securing the latter in position of adjustment to the support 188.

The rear end of the shaft 190 is formed with a bifurcated head 262 in which a leg 263 is supported for pivotal adjustment about a stud 264. A coiled compression spring 265 disposed in a bore 266 in the rear end of the shaft 190 abuts against the leg 263 below the stud 264 and serves to hold the leg yieldingly in a substantially vertical position. A triangularly-shaped head 267 is mounted on the upper end of the leg 263 and extends transversely thereof over the grinding wheel B. Extending through the head 267 is an operating shaft 268 with a gear 269 secured to the rear end in a circular recess 270, and a hand lever 271 secured to the front end.

Two relatively inclined guideways 272 and 273 are formed in the rear end of the head 267, and intersect each other at the angle subtended between the side faces of the grinding wheel B and also intersect opposite sides of the recess 270. Slidably disposed in the guideways 272 and 273 and held therein by an outer cover plate 274 are two gear racks 275 and 276 in mesh with the gear 269. The lower ends of the racks 275 and 276 are reduced in width and cross each other, and carry suitable dressing tools 277 and 278 for the oppositely inclined surfaces of the grinding wheel B. The racks 275 and 276 are so positioned relatively to each other that when one tool 278 is at its uppermost limit of travel, the other tool 277 is at

its lowermost limit of travel, thus avoiding interference.

Provision is made for automatically feeding the dressing tools 277 and 278 toward the grinding wheel B in timed relation to the rearward incremental feed of the latter toward the blank A in the course of the grinding operation. To this end, the lower end of the leg 263 is disposed in the path of a stop screw 279 adjustably secured in the upper end of a vertical arm 280. The latter is formed on one end of a supporting bar 281 rigidly secured to one side of the slide 195 for adjustment longitudinally thereof. It will be evident that as the grinding wheel B is fed rearwardly to depth by the slide 193, the head 267 will be tilted rearwardly through coaction of the leg 263 with the relatively fixed screw 279, thus advancing the dressing tools 277 and 278 toward the grinding wheel. For the initial cut at the start of the grinding operation, the periphery of the wheel is blunt. As the grinding operation proceeds to full depth, the cutting contour of the wheel B becomes sharper and sharper upon repeated dressing until the final V-shaped form is reached.

Relieving mechanism

Means is provided for effecting a relative relieving reciprocation between the blank A and the grinding wheel B transversely of the blank 30 once for each tooth as it passes through the grinding zone, and for separating the blank and the grinding wheel during each indexing movement and during the free-return stroke (see Figs. 8 and 12 to 15). To this end, the supporting 35 or relieving slide 195 carrying the grinding wheel B is mounted for reciprocation on horizontal transverse ways 282 formed on the machine frame 31. A heavy coiled compression spring 283 is interposed between an inner wall 284 of the frame 31 and an adjustable plug 285 in a depending lug 286 on the underside of the slide 195, and tends to urge the grinding wheel B away from the blank A.

Pivoted secured at its upper end to the rear 45 end of the slide 195 is a depending cam lever 287 normally fulcrumed about its lower end. A cam follower block 288 is secured to the lever 287 intermediate its ends, and rides on a rotary relieving cam 289 having a spiral face *a* terminating in an abrupt drop *b*. The cam 289 is secured to a longitudinal shaft 290 journaled at its ends on the machine frame 31 and connected at its left end through a train of speed-change gears 291, 292, 293, and 294 (see Fig. 10) to the 55 main drive shaft 41. The rotation of the cam 289 is so timed to the blank A that the grinding wheel B will be fed rearwardly during the grinding of each tooth so as to generate a suitable radial relief, and will then be returned quickly 60 to initial position for the succeeding tooth.

The lower end of the lever 287 is fulcrumed against a roller 295 mounted in the bifurcated front end of a plunger 296 slidably disposed in a bearing 297 on the rear of the machine frame 31. The rear end of the plunger 296 rides on a rotary separating cam 298 having a peripheral dwell face *c* of substantially 180°, a peripheral dwell face *d* of smaller radius also of approximately 180°, an abrupt drop shoulder *e* and a gradual rise shoulder *f* connecting the ends of said dwell faces. Upon rotation of the cam 298 in a counter-clockwise direction as viewed in Fig. 12, movement of the drop shoulder *e* past the 75

plunger 296 permits the spring 283 to withdraw the grinding wheel B quickly from the blank A into remote inoperative position, the lever 287 fulcruming about the cam follower 288. The 5 grinding wheel B is retained in this position while the dwell face *d* rides past the plunger. The inclined rise shoulder *f* returns the grinding wheel B to operative position by fulcruming the lever 287 about the block 288, and the dwell 10 face *c* retains the grinding wheel in this position.

The cam 298 is rotatably mounted in suitable anti-friction bearings on a fixed shaft 299 mounted in spaced brackets 300 and 301 on the rear of the frame 31. A gear 302 (see Figs. 14 and 15) is rotatably mounted on the hub of the cam 298, and carries a pivotal pawl 303 spring-pressed into engagement with a notch 304 in the periphery of the hub for rotation therewith in a clockwise direction as viewed in Fig. 15. The 20 gear 302 meshes with a gear 305 on the right end of the shaft 60 which is suitably journaled in a bearing 306 on the bracket 301. Thus, the cam 298 is driven in timed relation to the blank A during the grinding stroke. In the present 25 instance, the cam 298 makes one complete revolution for two of the blank A, the cam faces *c* and *d* serving to locate the grinding wheel respectively in and out of cutting position during alternate revolutions of the blank. During the 30 return stroke of the blank A, the cam 298 is idle, and is positioned with the cam face *d* in engagement with the plunger 296 so as to hold the grinding wheel B out of engagement with the blank.

35 For manual operation, the cam 298 is locked in position with the cam face *c* in engagement with the plunger 296 to locate the grinding wheel B normally in cutting position. Preferably, the means for this purpose comprises a lock pin 307 40 slidably mounted in the bracket 300 for movement into a hole 308 in the adjacent side face of the cam 298. Separation of the grinding wheel B from the blank A may be effected when desired by means of the lever 213.

45 Résumé of operation

The machine may be adjusted for full automatic operation, semi-automatic operation or manual operation.

50 In the set-up of the machine for full automatic operation, the clutch 103 (Fig. 9) is closed; the bar 150 is adjusted to compensate for the inclination of the gashes on the blank A; the pawl 175 is removed from the lever 161 so that the clutch 65 will remain closed; the lever 213 55 is adjusted to position the feed slide 193 in its rearward position for control by the cam 298; the pawl 242 (Fig. 2) is in engagement with the ratchet 240 to connect the automatic feed; the pin 307 is out of engagement with the cam 298; the work spindle 38 is adjusted into correct relation to the cams 289 and 298; and the grinding wheel B is positioned at the proper depth to take an initial cut along the first groove at 60 the right end of the blank A. At the start, the grinding wheel B has a blunt contour. If the blank A is tapered longitudinally, the gear 257 is brought into engagement with the gear 234 and the pin 235 is retracted from the latter to 65 connect the shaft 254 to the feed screw 196.

The power drive is now connected. Thereupon, the blank A is rotated in a counter-clockwise direction as viewed in Fig. 12, and the grinding wheel B is reciprocated by the cam 289 transversely of the blank once for each tooth to pro-

vide the desired relief. After one complete revolution of the blank A, the grinding wheel B is retracted into inoperative position by the cam 298, and during the next revolution of the blank it is indexed to the right to position the next 5 groove in registry with the grinding wheel. After completion of the indexing movement, the grinding wheel B is returned into operative position through the action of the cam 298.

The foregoing operation is repeated until the 10 blank A has been indexed its full length across the grinding wheel B for the initial cut. At this point, the pneumatic motor 108 is actuated to reverse the clutch (not shown) in the main power drive, and the clutch 89—90 (see Fig. 16). As a 15 result, the rotation of the spindle 38 and the shaft 60 is reversed, and the indexing screw 96 is driven in the opposite direction to return the blank A at a relatively high speed in a continuous 20 movement to its initial position.

During this return movement, the Geneva motion device in the normal step-by-step indexing drive is inoperative, and the cam 298 is stationary, with the cam face *d* (Fig. 12) in engagement with the plunger 296 to position the 25 grinding wheel B out of engagement with the blank A. At the end of the return movement, the grinding wheel B is given an automatic incremental feed toward the blank A for the next longitudinal cut, and the pneumatic engine 108 30 is actuated to establish the initial connections. The grinding wheel B now is dressed. The resulting contour is somewhat sharper than the initial contour since the dressing device is advanced toward the grinding wheel B in timed 35 relation to the feed of the latter toward the blank A.

The foregoing cycle of operations is repeated until the blank A is ground to the desired depth. At the end of the operation, the contour of the 40 grinding wheel will be the same as the desired contour of the teeth on the blank A. If the taper drive is connected, the grinding wheel B will be advanced toward the blank A in timed 45 relation to the step-by-step indexing movement to compensate for the angle of the taper on the blank.

The set-up for semi-automatic operation is the same excepting that the pawl 175 is mounted on the lever 161 (Fig. 25). In operation, the 50 handle 166 is actuated to close the clutch 65 to institute the indexing operation, and the pawl 175 through coaction with the star wheel 168 is effective to open the clutch 65 at the end of each indexing movement. Semi-automatic operation 55 places the indexing under manual control. In all other respects, the operation is the same as the full automatic operation. Manual control of the indexing is desirable when setting up the machine for full automatic operation, and particularly to facilitate correctly positioning the grinding wheel B relative to the grooves between the teeth on the blank A.

In the set-up for manual operation, the air supply to the motor 108 is shut off; the clutch 103 60 in the drive for the indexing screw 96 is open; the pawl 175 in the operating mechanism for the clutch 65 is removed; the pawl 242 (Fig. 2) is moved into inoperative position to disconnect the automatic feed; the gear 305 in the drive for the 65 cam 298 is removed; and the cam 298 is locked in position by the pin 307 with the cam face *c* in engagement with the plunger 296.

The power drive is connected to drive the spindle 38 and the relieving cam 289. The lever 213 70

is actuated to withdraw the grinding wheel B from the blank A to permit indexing and the free return movement. The blank A is traversed longitudinally by turning the shaft 254. The 5 grinding wheel B is fed toward the blank A by turning the hand wheel 239. It will be evident that in the manual operation, the automatic feed for the grinding wheel B may be connected, and that other specific automatic features may be 10 utilized.

I claim as my invention:—

1. A machine for form and relief grinding rotary cutters having generally longitudinally inclined gashes and a plurality of longitudinally spaced annular rows of teeth comprising, in combination, a rotary shaft for supporting the cutter blank, means including a differential mechanism for rotating said shaft, a slide mounted for rectilinear movement perpendicularly to said 15 shaft, a grinding wheel mounted on said slide, means acting on said slide for automatically effecting a relieving reciprocation between said wheel and the blank once for each tooth being ground, means for automatically effecting a 20 relative step-by-step indexing movement between said wheel and the blank longitudinally of the latter and in timed relation to the rotation of the blank to present different rows of the teeth successively to said wheel, and means 25 for automatically adjusting said differential mechanism during each step in said indexing movement to compensate for the inclination of said gashes.

2. A machine for form and relief grinding rotary cutters having generally longitudinal gashes and a plurality of longitudinally spaced annular rows of teeth comprising, in combination, a rotary support for the cutter blank, means for rotating said support, a grinding wheel, and 30 means for automatically effecting a relative step-by-step indexing movement between said wheel and the blank in one direction longitudinally of the blank and in timed relation to the rotation of the blank to present consecutive rows of the 35 teeth successively to said wheel, and for automatically effecting a relative continuous return movement between said wheel and the blank in the other direction longitudinally of said blank at the end of said step-by-step movement, and 40 means for automatically effecting a relative separation between said wheel and the blank once during each step of said indexing movement and during said return movement.

3. A machine for form and relief grinding rotary cutters having generally longitudinal gashes and a plurality of longitudinally spaced annular rows of teeth comprising, in combination, a rotary support for the cutter blank, means for rotating said support, a grinding wheel, and 45 means for automatically effecting a relative reciprocatory movement between said wheel and the blank longitudinally of the blank and in timed relation to the rotation of the blank, said movement in one direction being intermittent to present consecutive rows of the teeth successively to 50 said wheel and in the other direction serving to return said wheel and the blank to initial position, means for automatically effecting a relative separation between said wheel and the blank once during each step of said intermittent movement and during the return movement, and means for automatically effecting a relative incremental feed of said wheel toward the blank 55 once for each complete reciprocation.

4. A machine for form and relief grinding

rotary cutters having generally longitudinal gashes and a plurality of longitudinally spaced annular rows of teeth comprising, in combination, a rotary support for the cutter blank, means for rotating said support, a grinding wheel, and 5 means for continuously effecting an automatic relative reciprocatory movement between said wheel and the blank longitudinally of the blank and in timed relation to the rotation of the blank, said movement in one direction being intermittent to present consecutive rows of the teeth successively to said wheel and in the other direction being uninterrupted and serving to return said wheel and the blank to initial position, means for effecting a relative separation between said wheel and the blank once during each step of said intermittent movement and during the return movement, and means for effecting a relative incremental feed of said wheel toward the blank 10 once for each complete reciprocation.

5. A machine for relief grinding a work blank having generally longitudinal gashes and a series of longitudinally spaced peripheral rows of teeth comprising, in combination, a grinding wheel, a rotary support for the blank, means for effecting a relative relieving reciprocation between said wheel and the blank laterally of the blank, means for effecting a relative step-by-step indexing movement between said wheel and the blank in one direction longitudinally of said blank, means for effecting relative free return indexing movement in the opposite direction between the wheel and the blank, and trip means automatically operable at the ends of said indexing movements to render said last two mentioned means 15 alternately operable and inoperable.

6. A machine for grinding rotary cutters having generally longitudinal gashes and a plurality of longitudinally spaced annular grooves comprising, in combination, a reversible power drive, a rotary support for the cutter blank connected to said drive, a grinding wheel, means connected to said drive for automatically effecting a relative reciprocation between said wheel and the blank longitudinally of said blank, said means including a slow intermittently acting indexing mechanism, a high-speed return mechanism, and a two-way clutch for selectively rendering one or the other of said mechanisms operative, trip means automatically operable at each end of said reciprocation to reverse said drive and said clutch, means for automatically effecting a relative relieving reciprocation between said wheel and the blank during the periods between the intermittent indexing movements, and means for automatically effecting a separation between said wheel and the blank during each intermittent indexing movement and during the return movement.

7. A machine for grinding rotary cutters having generally longitudinal gashes and a plurality of longitudinally spaced annular grooves comprising, in combination, a reversible power drive, a rotary support for the cutter blank connected to said drive, a grinding wheel, means connected to said drive for automatically effecting a relative reciprocation between said wheel and the blank longitudinally of said blank, said means including a slow intermittently acting indexing mechanism, a high-speed return mechanism, and a two-way clutch for selectively rendering one or the other of said mechanisms operative, pneumatic trip means automatically operable at each end of said reciprocation to reverse said drive and said clutch, means connected to said drive for automatically effecting a relative relieving reciprocation be- 75

- 5   between said wheel and the blank during the periods between the intermittent indexing movements, and means connected to said drive through a one-way clutch for automatically effecting a separation between said wheel and the blank once during each intermittent indexing movement and during the return movement.
- 6   8. A machine for grinding rotary cutters having generally longitudinal gashes and a plurality of longitudinally spaced annular grooves comprising, in combination, a power drive, a rotary support for the cutter blank, a grinding wheel, means connected to said drive for automatically effecting a relative reciprocation between said wheel and the blank longitudinally of said blank, said means including an intermittently acting indexing mechanism, a return mechanism, and a clutch for selectively rendering one or the other of said mechanisms operative, trip means automatically operable at each end of said reciprocation to reverse said clutch, and means for automatically effecting a relative relieving reciprocation between said wheel and the blank during the periods between the intermittent indexing movements, and means for automatically effecting a separation between said wheel and the blank during any relative longitudinal movement.
- 7   9. In a grinding machine, in combination, a support, a slide on said support, a grinding wheel mounted on said slide, a dressing device mounted on said slide for pivotal movement generally in the plane of said wheel and having a dressing tool movable toward or from the periphery of said wheel upon said pivotal movement, an arm on said device, and an adjustable stop on said support in engagement with said arm and operable to swing the latter in timed relation to the movement of said slide on said support.
- 8   10. In a grinding machine, in combination, a support, a slide on said support, a spindle on said slide, means including a shaft for driving said slide, a cross slide on said support, a feed screw for said cross slide journaled in said support, means including a differential mechanism for actuating said feed screw, said mechanism having a terminal gear, a gear rigid with said terminal gear, spring detent means for releasably locking said last mentioned gear in fixed position, and means available at will for gearing said shaft to said last mentioned gear.
- 9   11. In a grinding machine, in combination, a base, a rotary spindle on said base, a relieving slide on said base reciprocable transversely of said spindle, a relieving cam journaled in said base, a lever pivoted at one end to said slide and engaging intermediate its ends with said cam, a spring for urging said lever against said cam, a plunger reciprocable in said base, one end of said plunger constituting an abutment for the other end of said lever, a separating cam journaled on said base and engaging the other end of said plunger, and means for rotating said cams.
- 10   12. In a grinding machine, in combination, a base, a rotary spindle on said base, a relieving slide on said base reciprocable transversely of said spindle, a relieving cam journaled in said base, a lever pivoted at its upper end to said slide and engaging intermediate its ends with said cam, a spring for urging said lever against said cam, a plunger slidable in said base, one end of said plunger constituting an abutment for the lower end of said lever, a separating cam engaging the other end of said plunger, means for driving said relieving cam in timed relation to said spindle, and means including a one-way clutch for turning said separating cam through one complete revolution for every two revolutions of said spindle.
- 11   13. In a grinding machine, in combination, a base, a relieving slide on said base, a relieving cam for reciprocating said slide, a feed slide on said relieving slide, a spindle journaled in said feed slide, a feed screw for said feed slide, said feed screw having a head rotatably and slidably mounted in said relieving slide, a draw bar extending through said screw and anchored to said relieving slide, a spring tending to move said head in one direction in said relieving slide, and a cam lever pivoted to said bar and available to move said screw in the other direction against the action of said spring.
- 12   14. The method of relief grinding a work blank having generally longitudinal gashes and a series of longitudinally spaced annular rows of teeth which comprises rotating the blank in one direction, effecting a relative relieving reciprocation between said wheel and the blank in timed relation to the rotation of said blank, effecting a relative step-by-step indexing movement between said wheel and the blank in one direction longitudinally of said blank and once for each complete grinding revolution of the blank, separating said wheel from the blank at the end of said indexing movement, then effecting a relative continuous return indexing movement between said wheel and the blank in the opposite direction, and during said return movement effecting a relative feed of said wheel toward the blank for the next cut along the blank.
- 13   15. In a grinding machine, in combination, a base, a rotary spindle for a work blank, a support for said spindle movable on said base axially of said spindle, a slide mounted on said base for movement transversely of said spindle, means for moving said support, a rotary screw for feeding said slide, a planetary gear transmission connected to said screw, a power drive adapted to be connected at will to said transmission to feed said slide in timed relation to the movement of said support, and drive means connected to said transmission and operable in response to movement of said support into a predetermined position to impart an incremental feed to said screw.
- 14   16. A grinding machine for a rotary work blank having generally longitudinal gashes and a series of longitudinally spaced peripheral rows of teeth comprising, in combination, a base, a rotary support for the blank, a carriage for supporting said support and mounted on said base for reciprocatory movement axially of said blank, a rotary grinding wheel mounted on said base in operative relation to said blank, drive means for rotating said support, and drive means for reciprocating said carriage, said last mentioned drive means including a driving element rotatable in timed relation to the rotation of said support, a driven translating element operatively connected to said carriage, a Geneva motion device, a two-way clutch selectively adjustable to connect said driving element directly to said driven element or said motion device to said driven element, a clutch for connecting said driving element to said device, and means for automatically actuating said first mentioned clutch reversely from one position to the other respectively upon movement of said carriage into its opposite end positions.
- 15   17. A grinding machine for a rotary work blank having generally longitudinal gashes and a series of longitudinally spaced peripheral rows

- of teeth comprising, in combination, a base, a rotary support for the blank, a carriage for supporting said support and mounted on said base for reciprocatory movement axially of said blank,
- 5 a rotary grinding wheel mounted on said base in operative relation to said blank, drive means for rotating said support, and reversible drive means for reciprocating said carriage, said last mentioned drive means including a driving ele-
- 10 ment rotatable in timed relation to the rotation of said support, a driven translating element operatively connected to said carriage, a Geneva motion device, clutch means selectively operable to connect said driving element directly to said
- 15 driven element or said motion device to said driven element, means for connecting said driving element to said device, and means rendering said motion device effective in only one direction.
18. A grinding machine for a rotary work blank
- 20 having generally longitudinal gashes and a series of longitudinally spaced peripheral rows of teeth comprising, in combination, a base, a rotary support for the blank, a carriage for supporting said support and mounted on said base for reciproc-
- 25 tory movement axially of said blank, a rotary grinding wheel mounted on said base in operative relation to said blank, drive means for rotating said support, and reversible drive means for reciprocating said carriage, said last mentioned
- 30 drive means including a driving element rotatable in timed relation to the rotation of said support, a driven translating element operatively connected to said carriage, a Geneva motion device, clutch means selectively operable to connect said
- 35 driving element directly to said driven element or said motion device to said driven element, means for connecting said driving element to said device, means rendering said motion device effective in only one direction, means operable automatically in response to movement of said car-
- 40 rriage into either end position to reverse said drive means and to actuate said first mentioned clutch means to change the drive connection to said driven element, and means operable from said driven member for automatically opening said
- 45 last mentioned clutch means after each of a series of predetermined step-by-step movements of said carriage in one direction.
19. A grinding machine for a rotary work blank
- 50 having generally longitudinal gashes and a series of longitudinally spaced peripheral rows of teeth comprising, in combination, a base, a rotary support for the blank, a carriage for supporting said support and mounted on said base for reciprocatory movement axially of said blank, a rotary
- 55 grinding wheel mounted on said base in operative relation to said blank, drive means for rotating said support, and reversible drive means for reciprocating said carriage, said last mentioned drive means including a driving element rotatable
- 60 in timed relation to the rotation of said support, a driven translating element operatively connected to said carriage, a Geneva motion device, clutch means selectively operable to connect said driv-
- 65 ing element directly to said driven element or said motion device to said driven element, means for connecting said driving element to said device, means rendering said motion device effective in only one direction, and means operable automatically in response to movement of said carriage
- 70 into either end position to reverse said drive means and to actuate said first mentioned clutch means to change the drive connection to said driven element.
20. A grinding machine for a rotary work blank

having generally longitudinal gashes and a series of longitudinally spaced peripheral rows of teeth comprising, in combination, a base, a rotary support for the blank, a carriage for supporting said support and mounted on said base for reciprocatory movement axially of said blank, a rotary grinding wheel mounted on said base in operative relation to said blank, drive means for rotating said support, and reversible drive means for reciprocating said carriage, said last mentioned drive

5 means including a driving element rotatable in timed relation to the rotation of said support, a driven translating element operatively connected to said carriage, a Geneva motion device, clutch means selectively operable to connect 10 said driving element directly to said driven element or said motion device to said driven element, clutch means for connecting said driving element to said device, means rendering said motion device effective in only one direction, means 20 operable automatically in response to movement of said carriage into either end position to reverse said drive means and to actuate said first mentioned clutch means to change the drive connection to said driven element, said last mentioned 25 clutch means being adapted to be closed manually, and means adapted to be rendered inoperable at will and when in operable condition to be actuated in timed relation to said driving element to open said last mentioned clutch means after each 30 of a series of predetermined step-by-step movements of said carriage effected by the drive through said motion device in one direction.

21. A grinding machine for a rotary work blank

35 having generally longitudinal gashes and a series of longitudinally spaced peripheral rows of teeth comprising, in combination, a base, a rotary support for the blank, a carriage for supporting said support and mounted on said base for reciprocatory movement axially of said blank, a rotary

40 grinding wheel mounted on said base in operative relation to said blank, drive means for rotating said support, and reversible drive means for reciprocating said carriage, said last mentioned drive means including a driving element rotatable 45 in timed relation to the rotation of said support, a driven translating element operatively connected to said carriage, a Geneva motion device, a two-way clutch selectively adjustable to connect said driving element directly to said driven element or said motion device to said driven element, a clutch for connecting said driving element to said device, means for automatically actuating said first mentioned clutch reversely from one position to the other respectively upon movement of said carriage into its opposite end positions, an actuator operable manually to close said last mentioned clutch, a gear driven from said driving element, a star wheel pivotally mounted eccentrically on said gear and movable into operative position for engagement with said actuator to open said last mentioned clutch, and abutment means on said base for indexing said star wheel into said position upon rotation of said gear through a predetermined degree.

22. A grinding machine for a rotary work blank

50 having generally longitudinal gashes and a series of longitudinally spaced peripheral rows of teeth comprising, in combination, a base, a rotary support for the blank, a carriage for supporting said support and mounted on said base for reciprocatory movement axially of said blank, a rotary

55 grinding wheel mounted on said base in operative relation to said blank, drive means for rotating said support, and reversible drive means for reciprocating said carriage, said last mentioned drive

75

- means including a driving element rotatable in timed relation to the rotation of said support, a driven translating element operatively connected to said carriage, an intermittent motion device, a 5 one-way drive connection between said driving element and said device, releasable means for locking said device in fixed position, and means automatically operable upon movement of said carriage into one end position to disengage said 10 carriage into the other end position to engage said releasable means and connect said driving element to said driven element.
- 15 23. A machine for relief grinding a work blank having generally longitudinal gashes and a series of longitudinally spaced peripheral rows of teeth comprising, in combination, a base, a carriage reciprocable on said base, a spindle journaled on 20 said base and extending axially in a direction parallel to the path of reciprocation, a grinding wheel mounted on said base in operative relation to said spindle, reversible power drive means, means operatively connected to said drive means 25 for automatically effecting a relative relieving reciprocation between said wheel and the blank laterally of the blank during movement of said carriage in one direction, means operatively connected to said drive means for rotating said spindle, means operatively connected to said drive 30 means for reciprocating said carriage with a relative step-by-step indexing movement between said wheel and the blank in said one direction and a relative free return indexing movement in the opposite direction, means including a 35 separating cam for automatically effecting a relative separation between said wheel and the blank once during each step of said step-by-step movement and during said return indexing movement, said last mentioned means having a separable connection with said drive means, and means available at will for locking said separating cam in fixed position.
24. A machine for grinding a rotary work blank 40 having longitudinally inclined gashes comprising, in combination, a base, a carriage reciprocable on said base, a spindle on said carriage for supporting the blank and extending axially in a direction parallel to the movement of said 45 carriage, a grinding wheel supported on said base in operative relation to said spindle, drive means for reciprocating said carriage, a planetary gear mechanism mounted on said base and having an inlet gear operatively connected to said drive 50 means, an outlet gear having an axial spline drive connection with said spindle, and a normally fixed terminal gear coaxial with said spindle, and adjustable means having cooperative parts mounted on said base and said carriage 55 and operable to rotate said fixed terminal gear in timed relation to the carriage movement to compensate for the inclination of said gashes.
25. A machine for grinding a rotary work blank 60 having longitudinally inclined gashes comprising, in combination, a base, a carriage reciprocable on said base, a spindle on said carriage for supporting the blank and extending axially in a direction parallel to the movement of said carriage, a grinding wheel supported on said base in operative relation to said spindle, drive means, and a planetary gear mechanism mounted on 65 said base and having an outlet shaft axially splined to said spindle, an inlet gear rotatable on said shaft and connected to said drive means, an outlet gear fixed on said shaft, a terminal 70 gear rotatably mounted on said shaft, two rigidly connected coaxial gears pivotally mounted eccentrically on said inlet gear and meshing respectively with said outlet gear and terminal gear, a bracket mounted on said carriage, a guideway pivotally adjustable on said bracket into different angular positions in a plane parallel to the spindle axis, a block slideable in said guideway, a gear rack pivotally connected to said block and slideable in said base transversely of 75 said spindle, and a gear coaxial and rigid with said terminal gear and meshing with said rack.
26. A machine for grinding a rotary work blank having longitudinally inclined gashes comprising, in combination, a base, a carriage reciprocable on said base, a spindle on said carriage for supporting the blank and extending axially in a direction parallel to the movement of said carriage, a grinding wheel supported on said base in operative relation to said spindle, drive means, a planetary gear mechanism having an inlet gear operatively connected to said drive mechanism, an outlet gear having a drive connection with said spindle, and a normally fixed terminal gear coaxial with said spindle, and adjustable means having cooperative parts mounted on said base and said carriage and operable to rotate said fixed terminal gear in timed relation to the carriage movement to compensate for the inclination of said gashes.
27. In a grinding machine, in combination, a support, a carriage slideable on said support, a spindle journaled on said carriage, means for traversing said carriage, a cross slide on said support, a feed screw for said cross slide journaled in said support, and a planetary gear mechanism for actuating said feed screw, said mechanism having a terminal gear rotatable about said screw, a locking gear coaxial and rigid with said terminal gear, releasable locking means available at will for securing said locking gear in fixed position, means available at will for driving said terminal gear when said locking means is released, an outlet gear coaxial with and fixed on said screw, a carrier gear rotatable about said screw, two rigidly connected coaxial gears journaled eccentrically in said carrier gear and meshing respectively with said terminal and outlet gears, a worm meshing with said carrier gear, and means for rotating said worm.
28. In a grinding machine, in combination, a support, a carriage slideable on said support, a spindle journaled on said carriage, means for traversing said carriage, a cross slide on said support, a feed screw for said cross slide journaled in said support, and means for driving said screw and including a differential mechanism having a terminal gear, releasable means available at will for locking said terminal gear in fixed position, means available at will for driving said terminal gear when released, a second terminal gear, releasable means adjustable into an inoperative condition or into an operative condition to drive said second terminal gear, and manual means for driving said second terminal gear.
29. In a grinding machine, in combination, a support, a carriage slideable on said support, a spindle journaled on said carriage, means for traversing said carriage, a cross slide on said support, a feed screw for said cross slide journaled in said support, and means for driving said screw and including a differential mechanism having a terminal gear, means for driving said terminal gear, a second terminal gear, and means for driving said second terminal gear.

30. In a grinding machine, in combination, a support, a carriage slidable on said support, a spindle journaled on said carriage, means for traversing said carriage, a cross slide on said support, a feed screw for said cross slide journaled in said support, means for driving said screw and including a differential mechanism having two terminal gears, means for driving one of said terminal gears in timed relation to the carriage movement, and means for driving the other of said terminal gears automatically through a predetermined increment in response to movement of said carriage into a predetermined position.
31. In a grinding machine, in combination, a base, a carriage slidable on said base, a feed screw journaled in said base and in operative threaded engagement with said carriage, means for driving said screw, a cross slide mounted on said base, a feed screw supported on said base and in operative threaded engagement with said slide, and means available at will for connecting said screws for synchronous rotation.
32. A machine for relief grinding a work blank having generally longitudinal gashes and a series of longitudinally spaced peripheral rows of teeth comprising, in combination, a base, a carriage reciprocable on said base, a work spindle journaled on said carriage, a screw journaled in said base and operatively engaged with said carriage, a drive mechanism mounted in said base and having an outlet shaft axially splined to said spindle and having a parallel connection to said

screw, said drive mechanism being automatically operable to effect a step-by-step indexing movement of said carriage in one direction, and a return movement in the other direction, a one-way clutch in said parallel connection, and a shaft adapted for manual actuation journaled in said base and operatively connected to said screw.

33. A grinding machine for a rotary work blank having generally longitudinal gashes and a series of longitudinally spaced peripheral rows of relieved teeth comprising, in combination, a base, a carriage reciprocable on said base, a work spindle journaled on said carriage, a cross slide mounted on said base for movement transversely of said carriage, a grinding wheel mounted on said cross slide in operative relation to the work spindle, a power drive, means including a relieving cam connected to said power drive and operable to effect a relieving reciprocation of said slide in timed relation to the rotation of said spindle, means connected to said power drive and including a separating cam for effecting a separation between said grinding wheel and said spindle periodically in timed relation to the spindle rotation and including means for indexing said carriage axially of said spindle during each separation, and means connected to said drive means for rotating said spindle, said last mentioned means including a separable adjustable connection for permitting angular phase adjustment of said spindle relative to said relieving and separating cams.

JOHN EDGAR.
